APPARATUS FOR CUTTING AND MOUNTING
FRAMES OF ADHESIVE-COATED MATERIAL ON CARDSRoger Connor and Hunter E. Hooe, Athens, Ohio,
assignors to The McBee Company, Athens,
Ohio, a corporation

Application December 28, 1948, Serial No. 67,713

3 Claims. (Cl. 164—87)

1

This invention relates to apparatus for punching out frames of adhesive-coated material and mounting the frames on statistical cards or the like in registry with die-cut openings formed in the cards.

In the use of statistical cards and the like, it is frequently desirable to combine with the card a microfilm of a record or other information pertinent to the card. This may be accomplished by providing each card with a die-cut opening and mounting a microfilm exposure within the opening. Thus, when it is desired to read the information on the microfilm, the card may be inserted in a suitable projection apparatus for reading the microfilm.

In mounting microfilm exposures in die-cut openings in statistical cards and the like, it is a common practice to mount on one side of the card, in registry with the die-cut opening, a rectangular frame of glassine or other suitable material coated on one side (facing the card) with a pressure-sensitive adhesive. Such rectangular frame overlaps the edges of the die-cut opening, and the microfilm exposure is mounted on the overlapping portions of the frame.

One method of performing the operations described above comprises feeding a strip of adhesive-coated material between a die plate having a die opening formed therein and a punching die, and actuating the punching die to punch out a frame of adhesive-coated material from the strip and to mount the frame on a card in registry with a die-cut opening formed in the card. In carrying out this method, difficulty results from the fact that the strip of adhesive-coated material has a tendency to adhere to the die plate, thus interfering with the speed and continuity of operation.

It is an object of the invention to provide a means of overcoming the above-mentioned difficulty.

This and other objects of the invention will be apparent from the ensuing description and the appended claims.

Certain forms which the invention may assume are exemplified in the following description and illustrated by way of example in the accompanying drawings, in which:

Fig. 1 is a view, partly inside elevation and partly broken away, of one form of apparatus of the invention.

Fig. 2 is a fragmentary, sectional view of another form of apparatus of the invention.

Referring now to the drawings, and more particularly to Fig. 1, one form of apparatus, generally designated as 10, is illustrated which embod-

2

ies the improvements of this invention. This apparatus is adapted to punch out rectangular segments from a strip of adhesive-coated glassine, to mount the same upon a card, to punch the card and to perform an inner punch on the mounted segment of glassine. A novel and useful article is thus produced which is described and claimed in our copending application, Serial No. 67,712, filed December 28, 1948 entitled "Apparatus and Method of Cutting Adhesive Material and Mounting the Same Upon a Card."

This apparatus comprises a frame or housing 11 containing within a card punching mechanism 12 and without, a frame punching mechanism 13. The card punching mechanism, briefly, comprises a punching die 14 reciprocable in an opening 15 formed in a card supporting plate 16 upon which a card 17 is supported and is aligned by means of guide members 18. Springs 19 normally hold the die 14 in retracted position, and the die is actuated by means of a lever 20 and arm 29 to punch a card 17.

The frame punching mechanism comprises outer and inner dies 25 and 26, the outer die being reciprocable in a frame 27 and held in retracted position by a spring 28, and the inner die 26 being reciprocable in the outer die and held in retracted position by a spring 29. A die plate 30 having a die opening 31 is provided, being spaced from the frame 27 and dies 25 and 26, to provide a feed throat 32. The dies 25 and 26 are actuated by the lever 20 through the medium of levers 33 and 34, a link 35 and an arm 36.

A strip 40 of adhesive-coated glassine is supplied to the dies 25 and 26 in the manner hereinafter described, and when the lever 20 is depressed a rectangular segment of glassine is punched from the strip and deposited on the card 17 and is punched again to form an inner and smaller rectangular segment. Further details regarding the apparatus as thus far described, the operation of the punching dies 14, 25 and 26 and the nature of the article produced are set forth in the copending application above-mentioned.

As indicated, the adhesive-coated glassine 40 will have a tendency to adhere to the die plate 30, thus interfering with operation of the machine. To obviate this tendency, a feed means is provided which will now be described.

The glassine 40 is available in the form of a roll of laminar tape 41 comprising a glassine layer 40 and a layer of backing 42. This tape is supported on a reel 43 rotatably supported on a bracket 44. The backing is peeled in the usual

manner by means of a stripper plate 45 and a drive roll 46 rotatable by means of a knob 47. The peeled glassine is fed through the feed throat 32, and the resulting ladder 48 of waste is taken up by a take-up reel 49 rotatably mounted on a bracket 50. The take-up reel is driven by a knob 55, and the reels 43 and 49 may be synchronized and the feeding of the tape indexed by any suitable means well known in the art.

As illustrated, rollers 56 and 57 are rotatably mounted on the frame 27 on opposite sides of the punching dies, and the reels 43 and 49 are disposed with their axes above the feed throat 32. It will thus be apparent that the glassine strip 40 and ladder 48 will always be held taut against the rollers 56 and 57, and that when the dies 25 and 26 are actuated they will stretch the glassine. When the outer die 25 has completed its punching operation and is moving the punched segment of glassine down through the die opening 31, the adhesion of the glassine to the surface of the die plate 30 will be opposed by the tension of the glassine. This tension, arising from its stretching, will suffice to lift or snap the glassine back to its normal position and free it from the die plate 30 in ample time for the next increment of movement of the tape 41.

Referring now to Fig. 2, the construction there illustrated is similar, but a collar 60 carrying the rollers 56 and 57 is mounted on the outer die 25 so as to move therewith, and the upper die assembly is reciprocable in a frame 61. It will be apparent that when the dies 25 and 26 are actuated, the rollers 56 and 57 will carry the glassine strip 40 and ladder 48 down onto the die plate 30, and that when the dies return to their normal, retracted position the pressure of the rollers will be removed and the tension of the glassine will restore it to its normal position clear of the die plate.

It is thus apparent that an apparatus has been provided which is operable to punch segments or frames of adhesive-coated material from a strip thereof and to mount the segment or frame on a card or the like, and that a disadvantage of prior devices of this character is obviated, in that the strip and ladder of material are cleared of the die surfaces in ample time for the next cycle of operations.

While we have shown the preferred forms of our invention, it is to be understood that various changes may be made in its construction by those skilled in the art without departing from the spirit of the invention as defined in the appended claims.

Having thus described our invention, what we claim and desire to secure by Letters Patent is:

1. In a device of the class described for punching adhesive strip material, a frame, a fixed die plate on the frame, said die plate having a die opening therein, a die above the plate reciprocably mounted on the frame for movement toward and away from the die plate, means for feeding a strip of adhesive material between said die and plate and in spaced relation to each, a stop on the die, said means including a pair

of rollers disposed one on either side of the die and in contact with the side of the strip remote from the die plate, said means also including a roller mount carrying the rollers and being reciprocably mounted on the die and resting on said stop, the bottom surfaces of the rollers being disposed beneath the bottom surface of the die when the mount rests on said stop, spring means urging the mount against said stop, and means for moving said die toward and away from said die plate, whereby said rollers and therefore the portion of the strip between the rollers are likewise moved toward and away from said die plate.

2. In a device of the class described for punching adhesive strip material, a frame, a fixed die plate on the frame, said die plate having a die opening therein, a die above the plate reciprocably mounted on the frame for movement toward and away from the die plate, means for feeding a strip of adhesive material between said die and plate and in spaced relation to each, said means including a pair of rollers carried by the die with their bottom surfaces disposed beneath the bottom surface of the die and being disposed one on either side of the die and in contact with the side of the strip remote from the die plate, whereby when the die is moved toward and away from the die plate, said rollers and therefore the portion of the strip between said rollers are likewise moved toward and away from said die plate, and means for moving said die toward and away from said die plate.

3. In a device of the class described for punching adhesive strip material, a frame, a fixed die plate on the frame, said die plate having a die opening therein, a die above the plate reciprocably mounted on the frame for movement toward and away from the die plate, means for feeding a strip of adhesive material between said die and plate and in spaced relation to each, said means including a pair of rollers yieldably carried by the die with their bottom surfaces disposed beneath the bottom surface of the die and being disposed one on either side of the die and in contact with the side of the strip remote from the die plate, whereby when the die is moved toward and away from the die plate, said rollers and therefore the portion of the strip between said rollers are likewise moved toward and away from said die plate, and means for moving said die toward and away from said die plate.

ROGER CONNOR,
HUNTER E. HOOE.
